UNITED STATES PATENT OFFICE.

HARRY L. EICHHORN, OF CHICAGO, ILLINOIS.

WINDOW-OPERATING MECHANISM.

1,077,907.

Specification of Letters Patent.

Patented Nov. 4, 1913.

Application filed March 17, 1913. Serial No. 754,847.

To all whom it may concern:

Be it known that I, HARRY L. EICHHORN, citizen of the United States, residing at Chicago, in the county of Cook and State of Illinois, have invented certain new and useful Improvements in Window-Operating Mechanism; and I do hereby declare the following to be a full, clear, and exact description of the invention, such as will enable others skilled in the art to which it appertains to make and use the same.

My invention relates to window-operating mechanisms of the class having a sliding rod as a part of the mechanism, and consists of a novel clutch or locking device for holding the sliding rod of the window operator in rigid relation to other portions of the mechanism.

One object of my invention is to provide a simple lock or fastening for the sliding rod of a window operator, which will securely hold the rod against sliding, and which will not be dependent upon screws of any kind for the security of the fastening.

Another object is to provide a fastening for the sliding rod of a window operator which may be actuated by the hand operating the mechanism, thereby enabling the latter to be operated with one hand.

Still another object is to provide a fastening of this class having no unsightly projecting or protruding parts and one that will be both strong, simple and durable.

My invention is particularly adaptable for use with transom operators and casement window operators and is shown in both embodiments in the accompanying drawings, in which:

Figure —1— is a side view of a transom operator embodying my invention. Fig. —2— is an enlarged fragmentary view of portions of the embodiment shown in Fig. —1—. Fig. —3— is an enlarged horizontal section through the locking mechanism of the device shown in Figs. —1— and —2—. Fig. —4— is a similar view with the rod-locking clutch in its locking position. Fig. —5— is a section through Fig. —4— along the line 5—5. Fig. —6— shows a casement operator embodying my invention. Fig. —7— is an enlarged view, partially in section, of a portion of the operator of Fig. —6—. Fig. —8— is a section through Fig. —7— along the line 8—8. Figs. —9— and —10— are sectional views of an alternative

embodiment of the locking feature of my invention shown in two different positions.

In Figs. —1— and —2—, the device of my invention consists of a vertically positioned rod 1 slidably mounted in bearings 2 and 3 secured to the frame-work 4 of the window, the lower bearing 3 being in the form of a hollow sleeve, as shown sectionally in Fig. —2—. The portion of the sliding rod 1 projecting upwardly beyond the bearing 2 has at its end a clamp 5 swiveled thereto, the said clamp 5 being connected through levers 6 and 7 with the pivotally mounted transom or window 8. The clamp 5 has a portion 9 thereof slidably engaging a vertical guide 10 supported by the bearing 2 and bracket 11 vertically disposed above the said bearing. The operating rod 1 is angular, being preferably square in section, the perforations 12 in the upper and lower faces of the lower bearing or sleeve 3 being of sufficient diameter to permit the said angular rod readily to rotate with respect to the said sleeve. Within the sleeve 3, I position a clutch disk 13 consisting preferably of a circular disk having at its center a square opening slightly larger than the cross-section of the slideable rod 1, and having diametrically opposite portions 14 and 15 bent into substantially parallel planes at 16 an angle to the perforated central portion 17 therebetween.

Projecting radially inward from opposite sides of the sleeve 3 and separated by a space somewhat greater than the thickness 18 of the clutch disk 13 are upper and lower projections 17 arranged in pairs and adapted to engage the upper and lower surfaces of the disk 13 adjacent to its periphery. The adjacent surfaces of each pair of the projecting formations 17 are preferably parallel and transverse to the axis of the slideably mounted rod 1, thereby permitting the central portion 16 of the disk to rest horizontally upon these surfaces when the disk 13 is in the position shown in Fig. —2—, in which position the edges of the square perforations in the disk are substantially parallel to the sides of the rod 1, thereby permitting the latter to be slid freely through the said disk. When the rod 1 is rotated a quarter turn by means of the handle 18 at its lower end, coaction between the sides of the square central opening and the sides of the rod will cause the disk to rotate with 110

the latter, thereby bringing the projections 17 into engagement with the inclined portions 14 and 15 of the disk and tilting the perforated portion 16 of the latter at less than a right angle with the common axis of the sliding rod and of the bore 12 of the sleeve. Consequently, the square perforation in the disk 13 will be tilted so that two of its edges will clutch the sides 19 and 20 of the rod 1, as shown in Fig. —5—, thereby holding the rod in non-slidable relation to the sleeve 3. Since this sleeve is stationary with respect to the frame of the window, the sliding rod 1 and the window-moving levers 6 and 7 connected thereto will be held in fixed positions when the clutch 13 is thus interlocked with the rod and the sleeve encircling a portion thereof.

When the window is to be moved from its given position, the operating rod 1 is rotated a quarter turn by means of the handle 18, thereby rotating the disk 13 into its rod-slipping position, as shown in Fig. —2—, whereupon the rod may be moved freely in either direction and may again be secured in locked position by rotating the disk back a quarter turn in either direction. To prevent the clutch disk from being rotated with respect to the clutch-carrier or sleeve 3 by a jarring of the building, I preferably provide a spring 21 secured at its opposite ends to the clutch and the clutch-carrier, this spring being so positioned as to tend to hold the disk in its rod-clutching position, as shown in Fig. —4—, and to retract the disk to this position when the disk is rotated to its rod-slipping position, as shown in Fig. —3—.

When the device of my invention is to be used in connection with casement windows, the sleeve or clutch-carrier 22 may be mounted upon a tube 23 adapted to slide over an angular rod 24, the said tube and rod being connected at their outward ends by pivots 25 and 26 respectively to the frame 27 of the window and the window 28 pivoted upon said frame. In this embodiment, the sleeve 22 is rotatably mounted upon one end of the tube 23, as shown sectionally in Fig. —7—, thereby permitting the said sleeve or clutch-carrier to be manually rotated with respect to the rod 24 when the clutch 13 carried by the said sleeve is to be moved into or out of its locking engagement with the rod 24. In this case, the disk-retracting spring 29 is pictured in the form of a simple spiral coil around the exterior of the rod 24, which rod is slidably related to the tube 23 and the clutch-carrier mounted thereon. In this embodiment, the same hand which grasps and rotates the sleeve 22 can readily move the said sleeve endwise, thereby imparting the necessary motion to open or close the window, without requiring the use of the other hand or the manipulat-

ing of screws of any kind. Likewise, in the embodiment of Fig. —1—, the manipulation of the operator may be done entirely by the hand which rotates the handle 18 and which moves the same vertically in either direction, without requiring the use of the other hand or the manipulating of any screws or auxiliary fastening members.

While I preferably use my invention in embodiments permitting the window operator to be manipulated by the use of only one hand, I do not wish to be limited to this embodiment, as the device of my invention might also be applied to operators in which the rotating of the clutch member of the device was effected independently of the manipulation of the operating rod. For example, Figs. —9— and —10— show two sectional views of a clutch-carrier equipped with a clutch disk adapted to be manually rotated by means of a handle 30, the sliding rod in this case being separately manipulated by means of the other hand of the operator. Figs. —9— and —10— also show a spring 31 adapted to engage a peripheral notch 32 in the clutch-disk 13, thereby retaining the same in its rod-clutching position, as shown in Fig. —10—.

While I have shown and described the device of my invention as equipped with parallel-faced projecting formations 17 and with a clutch-disk having opposed portions tilted at an angle to the intervening portion of the disk, I do not wish to be limited to this particular arrangement, as other forms of coacting cam-formations might be provided upon the rotating clutch member of my device and upon the member carrying the same, for effecting the tilting of the former upon relative rotation of the said two members. Neither do I wish to be limited to a rod of square section, nor to other details of the drawings and description herewith, as the same might be modified considerably without departing from the spirit of my invention.

I claim as my invention:

1. In a window operating mechanism, a movable rod; means for transmitting the motion of the rod to a window to open or close the latter; and means for locking the rod against sliding; the said locking means comprising a sleeve mounted in slidable relation to the said rod, and a clutch carried by the sleeve and adapted, when tilted, to engage the rod; the sleeve and clutch being relatively rotatable, the sleeve being adapted to tilt the clutch into or out of its said engaging relation with the rod upon the said relative rotation of the clutch and sleeve.

2. In a window operating mechanism, a movable rod; means for transmitting the motion of the rod to a window to open or close the latter; and means for locking the

rod against sliding; the said locking means comprising a sleeve mounted in slidable relation to the said rod, and a clutch carried by the sleeve and adapted, when tilted, to engage the rod; the sleeve and clutch being relatively rotatable, there being coacting formations upon the sleeve and clutch for tilting the clutch into or out of its said engaging relation with the rod upon the said 10 relative rotation of the clutch and sleeve.

3. In a window operating mechanism, a movable rod; means for transmitting the motion of the rod to a window to open or close the latter; and means for locking the rod against sliding; the said locking means comprising a sleeve mounted in slidable relation to the said rod, and a clutch carried by the sleeve and adapted, when tilted, to engage the rod; the rod and clutch being relatively non-rotatable, but jointly rotatable with respect to the sleeve, there being coacting formations upon the sleeve and clutch for tilting the latter into or out of its said engaging relation with the rod upon 25 the said relative rotation of the rod and clutch with respect to the sleeve.

4. In a window operating mechanism, a slidably mounted rod; means for transmitting the sliding motion of the rod to a window to open or close the latter; and means for locking the rod against sliding; the said locking means comprising a sleeve mounted in slidable relation to the rod, and a movable clutch intermediate of the rod and the sleeve; the said clutch, when in one position, permitting the rod to slide freely relative to the sleeve; the said clutch, when in another position, lockingly engaging the rod relative to the sleeve; there being coacting formations upon the sleeve and the clutch for moving the sleeve from one to the other of the said positions upon relative rotation of the clutch with respect to the sleeve.

5. A lock for a window-operating mechanism actuated by a sliding rod, comprising a clutch-carrier and a clutch rotatably mounted therein, both encircling a portion of the said rod; there being coacting formations upon the clutch and clutch-carrier for moving the same into, or out of, parallelism upon relative rotation thereof; the said clutch having non-slidable engagement with the said rod in only one of the said positions; and spring means tending to hold the clutch in its said non-slidable rod-engaging position.

6. In a window operating mechanism, a slidably mounted rod; means for transmitting the sliding motion of the rod to a window to open or close the latter; and means for locking the rod against sliding; the said locking means comprising a sleeve mounted in slidable relation to the rod, and a movable clutch intermediate of the rod and the sleeve; the said clutch, when in one position,

permitting the rod to slide freely relative to the sleeve; the said clutch, when in another position, lockingly engaging the rod relative to the sleeve; there being coacting formations upon the sleeve and the clutch for moving the sleeve from one to the other of the said positions upon relative rotation of the clutch with respect to the sleeve; the said clutch being non-rotatable with respect to the rod, whereby a rotation of the rod will effect the said clutch-operating relative motion of the clutch and sleeve.

7. In a window operating mechanism, a movable rod; means for transmitting the motion of the rod to a window to open or close the latter; and means for locking the rod against sliding; the said locking means comprising a sleeve mounted in slidable relation to the said rod, and a clutch carried by the sleeve and adapted, when tilted, to engage the rod; the clutch and sleeve being relatively rotatable, one thereof having cam formations adapted to coact with formations upon the other thereof for tilting the clutch into or out of its said engaging relation with the rod upon rotation of the clutch relative to the sleeve.

8. A lock for a window-operating mechanism actuated by a sliding rod, comprising a clutch-carrier and a clutch mounted therein, both encircling a portion of the said rod; the clutch rotatable with respect to the clutch-carrier and adapted, when tilted relative to the clutch-carrier to interlock the rod and clutch-carrier in non-slidable relation to each other; there being coacting formations upon the clutch and clutch-carrier for moving the same into or out of the said tilted relation upon relative rotation of the same.

9. In a window operating mechanism, a slidably mounted rod; means for transmitting the sliding motion of the rod to a window to open or close the latter; means for locking the rod against sliding; the said locking means comprising a sleeve mounted in slidable relation to the rod, and a movable clutch intermediate of the rod and the sleeve; the said clutch, when in one position, permitting the rod to slide freely relative to the sleeve; the said clutch, when in another position, lockingly engaging the rod relative to the sleeve; there being coacting formations upon the sleeve and the clutch for moving the sleeve from one to the other of the said positions upon relative rotation of the clutch with respect to the sleeve; and spring-actuated means tending to prevent relative rotation of the clutch and sleeve when the clutch is in its rod-engaging position.

10. A lock for window-operating mechanism actuated by a sliding rod, comprising a stationary clutch-carrier; a perforated clutch disk rotatably mounted therein, diametrically opposed portions of the said disk bent in substantially parallel planes at an

angle to the portion of the disk therebetween; projections upon the clutch-carrier adapted to engage either the said opposed portions of the disk or parts of the said portion therebetween; the said rod freely slidable through the perforation of the clutch disk when the projections are in one of their said engaged relations, the said rod non-slidably engaged by the disk when the projections are in the other of their said relations.

11. A window operating mechanism comprising as one member a rod; as another member a clutch carrier mounted in slidable relation to the said rod; means connected to one of said members for transmitting relative motion of the said members to a window to open and close the latter; and means for locking the said members against relative sliding motion; the said locking means comprising a movable clutch carried by the clutch carrier, the said clutch when in one position, permitting the rod to slide freely relative to the clutch-carrier; the clutch, when in another position, lockingly engaging the rod to prevent the latter from sliding relative to the clutch-carrier; the clutch and clutch carrier being relatively rotatable; there being coacting formations upon the clutch and clutch carrier for moving the clutch into or out of its said locking relation with the rod upon relative rotation of the clutch and clutch carrier.

12. A window operating mechanism comprising as one member a rod; as another

member a clutch carrier mounted in slidable relation to the said rod; means connected to one of said members for transmitting relative motion of the said members to a window to open or close the latter; and means for locking the said members against relative sliding motion; the said locking means comprising a movable clutch carried by the clutch carrier, the said clutch, when in one position, permitting the rod to slide freely relative to the clutch-carrier; the clutch, when in another position, lockingly engaging the rod to prevent the latter from sliding relative to the sleeve; the clutch and clutch carrier being relatively rotatable; there being coacting formations upon the clutch and clutch carrier for moving the clutch into or out of its said locking relation with the rod upon relative rotation of the clutch and clutch carrier, the said members being manually rotatable with respect to each other, there being coacting formations upon the rod and the clutch for preventing the rod from rotating with respect to the said clutch, whereby a relative rotation of the said members will effect the clutch-actuating relative rotation of the clutch and clutch carrier.

In testimony whereof I have signed my name in presence of two subscribing witnesses.

HARRY L. EICHHORN.
